UNITED STATES PATENT OFFICE.

EZRA SMYTH, OF GREENCASTLE, INDIANA.

SWITCH-DERAILER.

SPECIFICATION forming part of Letters Patent No. 613,086, dated October 25, 1898.

Application filed March 12, 1898. Serial No. 673,593. (No model.)

To all whom it may concern:

Be it known that I, EZRA SMYTH, of Green-
castle, in the county of Putnam and State of
Indiana, have invented certain new and use-
ful Improvements in Switch-Derailers; and
I do hereby declare that the following is a
full, clear, and exact description of the invention,
which will enable others skilled in the
art to which it appertains to make and use the
same, reference being had to the accompany-
ing drawings, and to the letters of reference
marked thereon, which form part of this speci-
fication.

This invention has relation to safety
switches, and has for its object to prevent
cars left on switches or sidings from running
down upon the main track. This frequently
happens, either from neglecting to put on the
brakes, or from not chocking the car-wheels,
or in consequence of the car being blown by
storm-winds, or the loosening of the car from
its location by evil-minded persons, or from
other causes, by all of which a passing train
would be endangered. By my device the
main track is always kept clear of obstruction
at switches, thus removing the dread of
engineers at such points.

My invention consists of locating beyond
the switch, on the siding, a structure upon
which is located a derailing-switch so ar-
ranged as that when a car or train of cars are
switched off on said siding they are prevented
from running on the main track, as will be
hereinafter more fully described.

In the drawings, Figure 1 is a perspective
view showing my invention in position for de-
railing; Fig. 2, a plan view of the same, the
derailing-switch being locked; Fig. 3, a cross-
section taken on the line *x x*, Fig. 2; and Fig.
4 is a perspective view of one of the stand-
ards or supports for the derailing-switch.

In the drawings I only show one side of the
railway-siding, as the other side would be
simply a duplicate and therefore unneces-
sary.

The same letters will indicate like parts
throughout all the figures.

A is the rail, and B the cross-ties.

C are the standards or supports for the de-
railing-switch and switch-mate.

a are hinge-lugs to which the plate carry-

ing the derailer is hinged, and *b* are the in-
terlocking lugs forming the hinge and work-
ing between the lugs *a a*. The lugs *a* and *b*
are cast integral with their respective parts. 55

The supports C are firmly secured either by
plates *i i* or into the cross-ties B, or both, which
at this point are made wide, deep, and solid
for the better foundation of the structure, as
a shifting of these supports out of line would 60
seriously interfere with the proper working
of the device. These supports and hinges
secure the derailing-switch in its locked po-
sition, and when not in use the derailing-
switch is entirely out of the way, it being 65
thrown back, as shown in dotted lines. (See
Fig. 3.) It will be observed that the supports
C have an upper flat surface *c*, projecting in-
wardly at *d* under the switch-plate D for a
better and more secure bearing. 70

Having described the foundations, sup-
ports, &c., I will now describe the derailing-
switch, which comprise the plate D, the switch-
mate E, the ascending rail or rib F, the down-
wardly-projecting stay-plate G, and the ob-
lique plate H, having the cut-away *f*. All
these pieces are preferably cast in a single
piece, which at once makes the device much
cheaper and safer than if made out of sev-
eral pieces. 80

The locking-chain *g* is secured to the side
of the stay-plate and is locked into a loop or
staple *h*, fastened to the tie B, thus putting
it beyond the possibility of evil-minded per-
sons tampering with or loosening the derail-
ing-switch. Of course when the said switch
is not in use and thrown back it may also be
locked by the same chain to another staple,
so that only those having authority can place
and release the derailing-switch. 90

It will be observed that the derailing-switch
when placed solidly on the track, the rail or
rib F being on line on top of the railroad-
rail and the cut-away plate H lying obliquely
on and across it, the chain *g* holding it down 95
and the stay-plate G holding it securely from
lateral movement on one side, while the
hinges secure it on the opposite side, and
thus it is kept solidly in position against dis-
placement by the movement of the cars. 100

The operation is simple and is as follows:
The parts being preferably in place and the

switch open, the chain is unlocked. Then the plate D is raised, working in the hinges, and turned over on the railroad-rail, the rail or rib F and plate H resting on the said railroad-rail and the stay-plate G reaching down over and snugly fitting it against the side of the railroad-rail, then locking the chain to the staple h, where it remains until again unlocked. Thus any cars (one or more) should 10 move toward the main track (not shown) will be arrested by the derailing-switch, and if under great momentum they will be derailed and thrown from the siding, thus preventing them from running out on the main track and 15 leaving said main track free from obstruction as far as the switched-off cars are concerned.

It is obvious that slight changes and modifications may be made in the several parts without departing from the spirit of my invention. I therefore desire not to be confined to the exact form shown, but consider myself entitled to all such changes as lie within the scope of my invention.

Having described my invention, what I 25 claim, and desire to secure by Letters Patent, is—

1. In a switch-derailer for sidings, the plate D, provided with switch-mate E, cut-away

portion H, rail F, stay or safety plate G, and the hinged lugs b, substantially as set forth. 30

2. The derailer comprising the plate D, switch-mate E, plate H, and inclined plate F, adapted to rest on the railroad-rail, the safety or stay plate G, in combination with the hinged supports or standards C, all operating together substantially as set forth. 35

3. The combination in a derailer of the supports or standards C having hinged lugs a, the flat supporting-face c, and projection d, to support plate D, the latter having hinged lugs b, on one side, and safety or stay plate G, on its opposite side, the said hinges and supports preventing lateral movement of the derailer in one direction while the safety-plate G, prevents in the other, said hinges, supports and safety-plate G, being held in position by the plates D, and H, substantially as 40 described.

In testimony that I claim the foregoing as my own I affix my signature in presence of 45 two witnesses.

EZRA SMYTH. [L. S.]
